UNITED STATES PATENT OFFICE

WADE C. HAMILTON, OF VICKSBURG, MISSISSIPPI

COMBINATION BRACE AND BIT DRILL

Application filed December 21, 1926. Serial No. 156,173.

This invention relates to drill devices and pertains particularly to a bit brace designed to be converted to a hand or power drill.

A primary object of this invention is to provide, in a manner as hereinafter set forth, a bit brace so constructed that the same may be converted for use as a hand operated drill, or adapted to have a power cable attached thereto to set up a power drill.

10 Still another object of this invention is to provide in a manner as hereinafter set forth, the combination with a bit brace, of means for attaching an automatic feed mechanism to the chuck of the brace so that the device 15 may be converted into a self feeding power mechanism.

A still further object of the invention is to provide a combined hand operated bit brace and power mechanism of proper balance, durable and adapted to be easily converted from one use to another and comparatively inexpensive to manufacture.

Numerous other objects and advantages of the invention will become apparent as the description proceeds, and it will be best understood from a consideration of the following detailed description taken in connection with the accompanying drawings, forming a part of this specification with the understanding, however, that the invention is not confined to any strict conformity with the showing of the drawings, but may be changed or modified so long as such changes or modifications mark no material departure from the salient features of the invention as expressed in the appended claim.

In the drawings:

Figure 1 shows a bit brace in side elevation constructed in accordance with this invention.

Figure 2 is a longitudinal sectional view through the chuck and the casing head carried thereby.

Figure 3 is an enlarged sectional view taken upon the line 3—3 of Figure 2.

Figure 4 is an enlarged transverse section taken upon the line 4—4 of Figure 2.

Figure 5 is a transverse section taken upon the line 5—5 of Figure 3.

50 Figure 6 shows the brace chuck having the

crank removed therefrom and having the feed mechanism attached thereto preparatory to using the chuck as a power drill.

Figure 7 is a longitudinal sectional view through substantially the upper half of the structure shown in Figure 6, the section being taken upon the line 7—7 of Figure 6.

Figure 8 is a transverse section taken upon the line 8—8 of Figure 7.

Figure 9 is a transverse section taken upon the line 9—9 of Figure 7.

Figure 10 is a top plan view of a cap member used in connection with the feed mechanism for attaching a holding chain to the mechanism.

Figure 11 is a side elevation of the cap, and,

Figure 12 is another side elevation of the cap showing the manner in which the holding chain is attached thereto.

Referring now to the drawings in detail wherein like numerals of reference indicate corresponding parts throughout the several views, the numeral 1 indicates generally the bit brace chuck, carrying the gear encasing head indicated generally by the numeral 2.

The chuck 1 comprises the head 3 having formed in one end the axial threaded bore 4, this end of the head also being provided with the external screw threads as shown.

Threaded into the bore 4 of the head 3 is an adjustable nut 5 having a central tapered aperture formed therethrough to receive the tapered inner end of a bit, as indicated in dotted lines at 6 in Figure 2. It will be readily understood that by adjusting the nut 5 longitudinally of the bore 4, the same can be positioned to make bits of large or small size.

Threaded onto the head 3 is a chuck sleeve 7, the outer end 8 of which is of greater diameter than the inner end and the interior diameter of this outer portion 8 is further enlarged as indicated at 9 to receive the flanged portion 10 of the chuck jaw controlling collar 11, the inner wall of this portion 9 being threaded to receive the ring 12 surrounds the collar 11 to obstruct passage of the portion 10 of the collar to prevent the collar's removal.

The lower end edge of the head 3 is provided at diametrically opposite points with slots 13 which receive the shank of the jaw members 14, suitable pins 15 being passed through the shanks of the jaws to maintain the same in position in the slots 13. The backs of the jaws 14 fit in the grooves formed in the inner face of the surrounding collar 11 which grooves converge downwardly as shown in Figure 2 and from this it will be readily understood that upon threading the sleeve 7 inwardly upon the head 3 the collar 11 will be drawn inwardly also and will cause the lower ends of the jaws 14 to be moved together, the inner faces of the jaws being serrated to assist them in gripping the shank of a bit member.

The gear encasing head 2 comprises a hollow body mounted upon the upper end of the head 3, the lower wall 16 of this body being removable as shown, for access to the interior. At diametrically opposite points upon the casing side wall, sleeves 17 and 18 are formed which project from the wall and the sleeve 17 is closed at its inner end forming the socket 19, the wall of which is provided with screw threads, while the sleeve 18 opens directly through to the interior of the casing, as indicated at 20.

The outer end of the extended sleeve 17 is provided with screw threads while at diametrically opposite points, inwardly of the screw threads, is formed in the outer face of the sleeve, grooves 21 which communicate with passages 22 leading through the wall of the casing to the interior thereof. In each of the passages 22 is a pawl 23, the inner end of each pawl projecting to the central portion of the casing while the other end thereof has a finger 24 which extends outwardly and normally lies in a groove 21 in the adjacent sleeve. These pawls are pivotally held in position by pin members 25. Surrounding the inner portion of the sleeve 17 is a pawl actuating or controlling ring 26, the inner face of which is provided with notches 27 (Figure 5) into which the pawl fingers 24 are permitted to move under certain conditions hereinafter described.

A retaining ring 28 is threaded upon the outer end of the sleeve 17 to hold the pawl controlling ring 26 in the proper position.

The sleeve extension 18 has a cap 29 threaded thereover, which cap is of greater length than the sleeve and has an aperture 30 formed through the outer end thereof. When the cap 29 is threaded into position as shown in Figure 3 the face 31 is formed to receive the surrounding flange 32 of a power shaft 33, the inner end of which is slotted as indicated at 34 for engagement with the rib 35 of the stub shaft 36 positioned in the inner end of the passage 20 through the sleeve body 18. This power shaft 33 is attached when the brace struc-

ture is to be converted for use as a power drill, as will be hereinafter described.

A vertical stub shaft extends through the casing 2 as indicated by the numeral 37, the upper end of this shaft being enlarged as at 38 and extending through the top wall of the casing, the enlarged upper end of this shaft having a threaded bore formed therein. The lower end of this shaft extends through the lower wall 16 of the casing into the central portion of the head 3, to which it is fixed by the pin member 39.

Within the casing 2 there is positioned a pair of meshed beveled gears 40 and 41, the gear 40 being secured to the stub shaft 36 while the gear 41 is secured upon the vertical shaft 37. The shaft 37 also carries above the gear 41, a ratchet wheel 42 with the teeth of which the pawls 23 are adapted to engage, on opposite sides thereof, in the usual manner.

From the foregoing description it will be readily seen that by shifting the pawl controlling ring 26 so that both pawl fingers 24 might shift into the notches 27 of the ring, the pawls will be permitted to engage the ratchet wheel 42 and any turning movement given to the casing 2 will be imparted, through the shaft 37, to the chuck body 1. Shifting of the pawl controlling ring 36 will permit the turning of the casing in one direction to carry with it the chuck 1 while allowing the casing to idle in the opposite direction and the ring can also be shifted to permit the casing to revolve freely about the shaft 37 without turning the chuck body 1, as will be readily understood.

Mounted upon the top of the casing 2 is a nut body 43 having a stud 44 upon the under side thereof and adapted to be threaded into a threaded recess in the upper portion of the shaft 37. The top surface of this nut is provided with a threaded recess or bore for the purpose hereinafter set forth.

The usual bit brace crank is indicated generally by the numeral 45 and the arm 46 of this crank has its free end threaded for engagement in the bore 19 of the sleeve extension 17 to permit the use of the brace by hand in the usual manner. This crank arm 46 may be removed for the conversion of the tool to power use in the following manner.

The power shaft 33 is attached to the stub shaft 36 in the manner already described, and there is then employed in conjunction with the structures 1 and 2 an automatic feed mechanism indicated generally by the numeral 47, which mechanism will be hereinafter described in detail.

The feed mechanism used in connection with the structures 1 and 2 comprises a central shaft 48 having one end threaded in the recess of the nut 43 in alignment with the shaft 37 in the casing 2. A collar 49 surrounds the lower portion of the shaft 48

and is secured thereto by means of the set screw 50 which has projecting from the peripheral face thereof, a pin 51.

Surrounding the shaft 48 is an elongated sleeve 52, threaded throughout its length and terminating at the lower end in the surrounding relatively broad flange 53, a portion of which is flattened as at 54, and has projecting therefrom the stud 55 upon which is mounted a spur gear 56'. The flange 53 of the sleeve 52 is of greater diameter than the collar 49 as shown in Figures 6 and 7 and the spur 56 is designed to engage the pin 51 or rather the pin 51 engages between the teeth of the spur gear 56 when the sleeve and the flange portion integral therewith is revolved.

The upper end of the shaft 48 is reduced and threaded as at 54 to receive a nut 55' which nut retains about the upper end of the shaft and upon the upper end of the sleeve 52 a pair of disc members 56 which are held in spaced relation by bearing balls 57, the opposed faces of which discs are grooved to set up race ways for these balls.

Surrounding the lower portion of the sleeve 52 and resting upon the flange 53 is a plate body 58 having the periphery thereof formed to set up the teeth 59 designed to be engaged by the teeth of the spur gear 56', at all times. This plate 58 carries at diametrically opposite points, posts 60, which extend to and abut the under side of the lower one of the discs 56.

The sleeve 52 is threadably extended through the central part of a disc body 61, through which body the post 60 slidably extends, and the peripheral surface of this disc 61 is threaded to receive thereover an elongated housing body 62. The top of this housing body is closed and is formed to provide a pointed head 63.

As is well known, power operated drills are usually provided with means for holding the same against the work and there is provided for use in connection with this drill a cap 64 designed to fit over the head of the housing 62, which cap has extending from the side thereof a lug 65, provided at its under side with the slot 66 for the reception of one link of a chain body, a portion of which chain is shown and indicated by the numeral 67. The end link of this chain is inserted in the slot 66 and a pin is passed through the body 65 and through the link located in the slot.

Opposite the extension 65, an ear 68 is formed having a laterally opening slot 69 cut thereinto, in which slot another link of the chain 67 may be engaged in the manner shown in Figure 12. When in operation, as a power drill, when the tool is placed in position upon the work with the cap 64 upon the housing 62, the chain 67 having one end secured in the slot 66, is passed downwardly beneath the work and brought up upon the opposite side of the tool where one of the

links is engaged in the slot 69 in the manner shown. When the power shaft 33 is revolved rotary motion will be imparted to the shaft 37 and to the chuck 1 and also to the shaft 48. The collar 49 being rotated with the shaft 48 causes the pin, each time it passes beneath the spur gear 56', to slightly rotate this gear thus imparting rotary motion to the toothed plate 58 and causing the rotation of the housing 62 through the medium of the posts 60. The housing 62 is thus caused to move upwardly upon the threaded sleeve 52, against the cap 64 thus forcing the entire tool downwardly against the work upon which it is operating.

Having thus described my invention, what I claim is:

In a drill, a head, a shaft rotatably carried by said head, a chuck on one side of the head secured to the shaft for rotation therewith, means for rotating the shaft, a collar secured to the shaft on the opposite side of the head from said chuck, a laterally projecting pin carried by the periphery of the collar, an elongated exteriorly threaded sleeve surrounding and rotatably mounted upon said shaft beyond said head and collar, a flange formed on the inner end of the sleeve and resting upon said collar, an elongated housing inclosing said sleeve and having threaded connection therewith, a work engaging point formed on the outer end of said housing, said housing being designed to be held against rotary movement when the tool is in use by said work engaging point, a disc having the periphery thereof toothed resting upon said flange, a rigid connection between the disc and housing, a radially extending stub shaft carried by the periphery of the disc, and a toothed gear rotatably mounted on the stub shaft and having the teeth thereof normally meshing with the teeth of said disc, said gear being disposed to have said pin contact therewith at each revolution of the shaft to rotate said sleeve.

In testimony whereof I affix my signature.
WADE C. HAMILTON.
